UNITED STATES PATENT OFFICE.

FRANK E. CORNELL, OF NEW YORK, N. Y.

PAPER BOX FOR PACKING PAINTS, &c.

938,981.

Specification of Letters Patent.

Patented Nov. 2, 1909.

Application filed October 9, 1908. Serial No. 456,974.

To all whom it may concern:

Be it known that I, FRANK E. CORNELL, a citizen of the United States of America, residing in New York, in the borough of Brooklyn, county of Kings, and State of New York, have invented certain new and useful Improvements in Paper Boxes for Packing Paints and other Articles, of which the following is a specification.

10 This invention relates to an improved folding paper box which is intended to be used as a wrapper or outer package for paints and similar materials packed in cans, bottles or other containers, and which outer package permits the direct reading off of the contents of the box; and for this purpose the invention consists of a folding paper box made from a one-piece wrapper provided with a sample-window in the front-wall, and

15 a turned-in tongue or flap provided with a colored designating label for indicating the contents of the package placed in the paper box.

In the accompanying drawing, Figure 1 represents a perspective view of my improved folding paper box or outer package for paints and other materials, Fig. 2 is a vertical transverse section on line 2, 2, Fig. 1, and Fig. 3 is a plan view of the blank from which the paper box or outer package is made.

Similar letters of reference indicate corresponding parts throughout the figures of the drawing.

25 In marketing a line or assortment of paints or other merchandise in a large variety of colors, a large quantity of boxes or cartons has to be kept on hand with the name, number or color of each kind printed on the same. With a variety of 100 different colors, numbers or kinds, a large stock of paper boxes or packages is required in order to have a sufficient quantity of each kind ready at all times for wrapping or packing 30 the merchandise as the orders for the same are received. This requires a considerable expense for paper boxes for packing and causes also the frequent running short of boxes of one or the other particular color, 35 and in addition thereto a considerable amount of storage space for the large quantity and variety of packages required.

40 My improved paper box or outer package is designed to dispense with the necessity of keeping a large stock of boxes on hand, as 45 one style and size of box can be used for any

color, number or kind of paint or other material by simply printing an assortment of small and comparatively inexpensive labels indicating the designation, number and color 50 of the paints or other contents, which labels are affixed to the closing tongue or flap of the paper boxes or packages as the goods are packed in filling orders and replenishing stock. By this arrangement the individual 55 color, designation or number is visible through the sample-window, which is arranged in the front-wall of the box, the sample-window registering with the designation-label on the tongue or flap applied to 60 the top-wall of the box. This arrangement enables the manufacturer to provide a large 65 quantity of packages printed with the designation, color and number at a comparatively small expense and without crowding up the 70 storage-room for the goods.

The improved folding paper box or outer package is made of one integral blank, which in its general construction is similar 75 to the blanks of the well-known packing boxes on the market, and which consists of a creased blank formed of a front-wall a , side-walls a^1 and a rear-wall a^2 , the latter being provided with a gummed side-flap a^3 at its edge for being pasted onto one of the 80 side-walls a^1 . The side-walls a^1 are provided with top-flaps a^4 , each being of half the size of the side-flaps, and with bottom-flaps a^5 , also of half the size of the side-walls, which are turned inwardly so as to 85 form respectively the top and bottom of the folding paper box or package, in connection with a top-wall a^6 and bottom-flaps a^7 , which latter are provided respectively with anchoring slits a^8 and anchors a^9 for locking 90 over the bottom-flaps a^5 . The top-wall or cover is provided with a tongue or flap a^{10} on which is pasted a label a^{11} indicating the individual color, designation and number 95 of the contents of the can, bottle or other 100 container placed in the paper box. This tongue or flap a^{10} with its label a^{11} is inserted back of the front-wall a so as to close thereby the box at the top and front. In 105 the front-wall a is arranged an opening or sample-window a , of rectangular or other shape, which registers with the label a^{11} and renders it visible so as to indicate directly the 110 contents of the paper box. The opening or sample-window a in connection with the label on the inwardly-turned tongue or flap of the top-wall of the box form the essential

feature of novelty of my improved paper box or package. As shown, the lower and side edges of the label register with the corresponding edges of the flap α^{10} . This arrangement facilitates the placing of the labels in correct position on the flap to register properly with the window σ , since the edges of the flap form a convenient marking to indicate where the label is to go and a 10 convenient edge on which to rest the fingers to form a stop against which to place the label.

By making the color of the label correspond with the color, tint or shade of the 15 paint or other material and putting the name, designation or number in a suitable contrasting color on the colored background, the contents of the paper box can be quickly read off and determined; but it is obvious 20 that any label which indicates the color, designation or number of the contents can be used, the designation of the contents being printed, written, stamped or otherwise applied to the turned-in front-flap of the 25 top-portion of the box.

Having thus described my invention, I claim as new and desire to secure by Letters Patent:

1. A paper box having a hinged cover, a flap at the front-edge of said cover, a label applied to said flap, the front-wall of said box being provided with a window which registers with and forms a frame and protection for said label when said box is closed. 30

2. A paper box having a hinged cover, a flap at the front-edge of said cover, a label attached to said flap and having its lower and side edges registering with the corresponding edges of said flap, the front-wall of the box being provided with a window arranged to register with and form a frame and protection for said label through which the label is visible when the box is closed. 40

In testimony, that I claim the foregoing as my invention, I have signed my name in 45 presence of two subscribing witnesses.

FRANK E. CORNELL.
